METHOD AND MEANS FOR THE PREPARA-
TION OF SAMPLE CARDS CARRYING
KNOTTED SAMPLE THREADS

Ernst Erb, Basel, Switzerland

Application November 14, 1949, Serial No. 127,010
In Switzerland November 30, 1948

10 Claims. (Cl. 66--1)

1

Heretofore and generally speaking, sample cards are made by knotting sample threads or yarns of woolen and the like textile material inside the perforations or holes provided along edges of the sample cards so as to drop in front of the latter.

As the knotting of threads was heretofore done exclusively by hand, the procedure consisted merely in gluing the threads and yarns on the cards in the case of mass production. This forms the most rational method and consists in that the threads or yarns fed by warps prepared previously are glued between the actual sample card and a strip covering same while the different threads and yarns are cut to the desired length. This method has, however, the drawback that the sample cards obtained have an appearance that is poor with reference to sample cards carrying knotted threads.

For this purpose, it has been repeatedly attempted to execute mechanically the knotting of the threads over the perforations of a perforated strip, the threads being fed as precedingly from previously prepared warps. But such attempts have met with various difficulties leading always to faulty operation. Thus the hooks that are intended to draw the threads through the perforations in the perforated strip in order to give them a loop shape cannot, by reason of the reduced diameter of the perforations, have a size sufficient for producing a wide enough loop. As a consequence, the members that are to fetch the ends of the threads after passing through the loops for returning them again through said loops for fastening them cannot always be introduced through such narrow loops with certainty which prevents reliability in operation. It has, therefore, been proposed to provide further members such as pointed wedges inside the loops for widening same. But this leads in its turn to a greater number of operative steps and makes the plant a more intricate one.

Furthermore, it is not possible to obtain with such spacing or loop-opening means a perfectly reliable operation as the tips of the pointed wedges cannot reliably engage the loops when one of the hooks is shifted even to a very small extent out its actual normal position. Similarly, the different prior knotting methods have lead to substantial losses of the material to be knotted by reason of the hanging threads requiring a subsequent cutting to a uniform length which means also a further operative step.

Now, my invention has for its object a novel method and means for solving the above dis-

2

closed problem and cutting out all the causes or faulty operation. It is possible, thereby, to provide in short succession for the knotting of threads over different strips, the threads being fed from a previously formed warp without this leading to any loss of material.

In accordance with this method, the novel idea consists in that there are used for drawing the loops through the perforations of the sample card, two combs that are independent from one another and the superposed hooks of which are moved in the same direction so as to pass through the perforations in the perforated strip and to catch the warp threads advancing in front of said combs in order to give said threads simultaneously the shape of loops. Thus there are always two combs hanging on the loops thus formed of which one serves for holding the loop while the other comb fetches the ends of the threads and pulls them through the loops. As the second comb has already engaged the loops through its hooks, before it has taken hold of the warp thread ends, it is an easy matter to move it reliably through said loops so that it may take hold of the two ends of the thread corresponding to each loop, which ends have been laid during this first operative step side by side over the front of the perforated strip, said comb then drawing the thread ends through the loops that are held in place by the other card. A tightening of the loops at the end of the operation ensures the final fastening of the threads over the perforations of the sample card.

In other words, two independent combs hold in place the previously formed loops by means of one of said combs while the other comb is then caused to pass through the loops and to engage through its hooks the ends of the threads that are held fast for this purpose, the last mentioned comb urging then said thread ends over the edge of the perforated strip into the loops thus held by the first comb.

The novel features of the arrangement according to my invention and its operation are disclosed hereinafter, reference being made to accompanying drawings, wherein:

Fig. 1 is a view from above, partly sectional, of a comb adapted to take hold of the threads.

Fig. 2 is a view from above of a complete arrangement according to my invention, illustrated at the moment at which a comb carries the warp threads over the perforated strip that has been introduced into a support of said arrangement.

Fig. 3 illustrates diagrammatically in plan the

means provided for holding the perforated strips during the knotting operation.

Fig. 3a is a view, in end elevation, corresponding to Fig. 3.

Figs. 4, 5 and 6 are diagrams adapted to illustrate the actual operations of the knotting means.

The arrangement includes five similar thread-engaging and clamping combs including a number of hooks provided each with a pressing or clamping member. The combs designated respectively as 1a, 1b, 1c, 1d, 1e are all similar to the comb 1 illustrated in detail in Fig. 1. They are intended to catch and hold the warp threads and to draw said threads through the perforations in the perforated strips in order to form the desired loops and finally they are used for returning the ends of the threads through the loops formed by them to secure said threads in the perforations of the perforated strip.

Turning again to Fig. 1, 1 designates the actual comb body, 2 the hooks rigid with the latter, 3 the pressure members sliding vertically in openings provided in the comb and 4 a rail or the like member rigid with the different pressure members for controlling their simultaneous rising and sinking movements.

The hooks are rigid with the comb body 1 while, as stated, the pressure members may slide in the openings provided in said comb body.

The hooks 2 and the presser members 3 are distributed in accordance with a predetermined law of distribution corresponding to the distribution provided for the perforations in the perforated strip on which the sample threads are to be knotted. Fig. 1 illustrates the presser members 3 in their open position on the left hand side of said figure, while the right hand side of the comb shows sectionally the presser members 3 that are supposed to lie in their closed position for which the threads are clamped. Between the two halves of Fig. 1 is illustrated sectionally a presser member that has been submitted to a pivotal movement by 90° in order to appear in side view. Said part of Fig. 1 shows how the upper flange of the rail 4 engages the recess 5 of the rod 6 of the presser member 3 with the insertion of a spring 7 between the lower flange of the rail 4 and the lower end of the rod 6. Said spring 7 is wound over a stud 8 forming a lower extension of reduced diameter on the rod 6 of the presser member and the different springs 7 are designed in a manner such that the total power that may be exerted on the rail 4 may be distributed uniformly throughout the presser members whereby the latter are allowed to clamp threads of different thicknesses between the hooks and the corresponding presser member heads.

The rail 4 or the like member may be controlled pneumatically, electromagnetically, mechanically or else by hand as illustrated in the example of Fig. 1 where it is supposed that it is controlled through the agency of the lever 10. It is therefore not necessary to describe with further detail the arrangement for controlling said rail 4.

The presser members 3 are obtained through bending of a wire. They are guided in corresponding openings or grooves of the comb body and their heads 9 are guided over the stems 11 of the hooks 2. For this purpose and also for providing a suitable clamping of the thread, the head 9 of each presser member is centrally slotted at 12, so that said presser member may clamp the thread to either side of the hook 2 engaging said slot.

In order to clamp in a uniform and gradual manner the threads lying on the hooks, the heads 9 of the presser members are provided with an oblique surface obtained through a mere bending or folding deformation.

The tips of the hooks when closed over the presser member head engage the slot 12 in the corresponding presser member head. These hook tips are actually covered to either side thereof by the surfaces of the presser member heads facing them. This is in particular the case for the comb 1c (Fig. 6) so that the latter cannot engage and remain in hanging relationship inside the thread loop when it is urged back through said loop.

Fig. 3 shows a detail of the means for holding the perforated strips during operation. It consists chiefly in a carrier plate 14 provided with teeth 15 the distribution of which corresponds to the distribution of the hooks on the combs, the tips of said teeth being folded back so that the perforated strips 13 may be slidingly engaged underneath said tips and be thus held over the plate 14 throughout their length through their upper surface. In the case of perforated strips of different lengths, there are provided to either side of the latter stops 16 (Fig. 3) carrying spring blades 17 and capable of being mounted selectively in either of the perforations provided to this purpose at 18, 18'. The tongue 20 terminating the spring blade 17 is bent downwardly and bears yieldingly against the perforated strip 13 engaging the thread-holding arrangement or more accurately the plate 14 so as to prevent any undesired shifting of said strip.

Figs. 2, 4, 5, 6 illustrate diagrammatically the operation of the arrangement. Fig. 2 that is a view from above, corresponds to the moment at which the warp threads 21 are carried along by the comb 1a over the perforated strip 13 lying on the carrier plate 14. Said threads are fed through any suitable means that are not illustrated. The threads are guided and suitably distributed through the perforations 22 provided in the transversal guiding rail 23 and between the teeth of the cross member 24 lying in parallelism with and at a short distance from said guiding rail 23. The short guiding distance thus provided between the members 23 and 24 ensures the proper engagement of the hooks of the clamping combs with said threads.

Fig. 4 corresponds to the most important moment of operation, which moment is that at which the two combs 1b and 1c forming part of the system of five combs 1a, 1b, 1c, 1d, 1e are guided so as to pass together through the perforations in the perforated strip 13 and between the teeth of the plate 14 so as to take hold of the warp threads 21 stretched as disclosed over said perforated strip by the first comb 1a. Consequently, the combs 1b and 1c make the threads pass through the perforations in the perforated strip 13 and give them the shape of a loop 25 (Fig. 5). The warp threads are on the other hand previously taken hold of and clamped in register with the cross beam 26 through the two other combs 1d and 1e.

The thread warp is then cut between the two combs 1d—1e through the agency of a knife whereby the comb 1e forms and holds again an end of a thread warp, said comb 1e holding said warp until a further cycle of knotting operations begins over again with the threads of said warp. The comb 1d is now brought as illustrated in Fig. 5 above and into register with the comb 1a together with the ends of the threads

held thereby, whereby the two ends 26 of the thread forming the loop 25 come into superposed relationship by reason of the combs 1a-1d resting over one another to the front of the edge of the perforated strip. The combs 1b and 1c hang thus through their now open hooks inside the loops 25. The rear comb 1c is then raised somewhat and urged obliquely and upwardly through the loops 25 so as to take hold of the ends 26 of the threads that are already clamped by the combs 1a and 1b whereby said rear comb 1c clamps said ends 26. This being done, it is possible to release the pressing members of the combs 1a and 1b; the comb 1c is caused to carry the ends of the threads along with it and causes them to pass inside the loops 25. At this moment, the front comb 1b still retains the loops through its open hooks but it allows said loops to shrink while yielding in a uniform manner. Before the loops are completely closed through the operation of the comb 1c, said comb 1b is released. This release is obtained by moving said comb 1b towards the side corresponding to the backs of the hooks; consequently the loops are easily released while the tips of the hooks may be removed without being disturbed at any moment during the removal of the comb of which they form part.

The comb 1c serves then for urging into more intimate contact the loops over the perforated strip while fastening the knot that is shown in its first stage of formation in Fig. 6.

The combs 1a-1b-1c-1d are then released and removed from the threads and may be used for a further operation while the comb 1e is returned with its thread warp into the position corresponding to the position of the comb 1a in Fig. 2 after positioning of a further perforated strip on the plate 14.

It is also possible to lay side by side several combs so as to form comparatively long bars whereby it is an easy matter to perform the simultaneous knotting of a number of perforated strips through the same stages of operation and the same movements.

Figs. 4, 5 and 6 are diagrammatic showings of different locations of the combs corresponding to the different stages of operation. It is however possible, within the scope of the invention, to control mechanically said combs so as to obtain an automatic operation of the arrangement.

What I claim is:

1. In a method for knotting threads on perforated strips in order to produce sample cards, the steps of clamping the threads of a cut warp sheet lying on one side of a perforated strip on two independent hook carrying combs, the hooks of which extend through the corresponding perforations of a perforated strip and drawing said threads through said perforations for forming loops on the further side of the strip, turning the cut ends of the warp threads back so that they lie over the free ends thereof, releasing one of the combs with reference to the threads, urging said comb through the loops to engage the ends of the threads remaining on the first side of the strip, and returning the last mentioned comb through the loops to tighten the threads over the edge of the strip, releasing the other comb from the threads and removing both combs away therefrom.

2. In a method for knotting threads on perforated strips in order to produce sample cards, the steps of clamping the hooks provided on two independent combs on the threads of a cut

warp sheet, causing the thread-clamping hooks of both combs to pass through the corresponding perforations of a perforated strip for forming loops on the further side of the strip, releasing the hooks of one comb with reference to the threads while leaving the stems carrying said hooks inside the corresponding loops, turning the cut ends of each thread to extend together over the edge of the strip nearest the perforations therein, urging the above mentioned hook stems through the loops to make the hooks thereon clamp the thread ends and returning the thread end engaging hooks through the loops, tightening the threads through action on last mentioned hooks over the edge of the said strip, and removing the hooks of both combs away from the threads engaged thereby.

3. A method for knotting threads on perforated strips for producing sample cards consisting in holding warp threads by means of three hook-carrying combs, one comb at the free ends of said threads and two combs at two points lying very near one another at distances from said free ends that are substantially equal to the length required for the knotting of the sample threads, laying the threads carried between the first comb and the other combs over a perforated strip, cutting the threads between the last two combs, engaging two further hook-carrying combs with their hooks extending through the perforations of the strip from the side of the latter opposed to the threads, turning the cut ends of the threads over the first mentioned free ends thereof to extend together with them over the edge of the strip that is nearest the perforations, clamping the threads on the hooks of both last mentioned combs and drawing back the two last mentioned combs with the thread-carrying hooks through the perforations to form a loop on the side of the strip opposed to the remainder of the threads, releasing the hooks of one of the last mentioned combs and urging the released hooks freely through the loops into engagement with the folded ends of the threads extending over the strip edge, removing the combs carrying the cooperating ends of the threads, drawing back the thread end engaging comb through the loops to tighten the threads inside their loops over the said strip edge, and removing the two combs engaging the loop.

4. A method for knotting threads on perforated strips for producing sample cards consisting in holding warp threads by means of three hook-carrying combs, one comb at the free ends of said threads and two combs at two points lying very near one another at distances from said free ends that are substantially equal to the length required for the knotting of the sample threads, laying the threads carried between the first comb and the other combs over a perforated strip, cutting the threads between the last two combs, engaging two further hook-carrying combs with their hooks extending through the perforations of the strip from the side of the latter opposed to the threads, turning the cut ends of the threads over the first mentioned free ends thereof to extend together with them over the edge of the strip that is nearest the perforations, clamping the threads on the hooks of both last mentioned combs and drawing back the two last mentioned combs with the thread-carrying hooks through the perforations to form a loop on the side of the strip opposed to the remainder of the threads, releasing the hooks of one of the

last mentioned combs and urging the released hooks freely through the loops into engagement with the folded ends of the threads extending over the strip edge, removing the combs carrying the cooperating ends of the first threads, drawing back the thread end engaging comb through the loops to tighten the threads inside their loops over the said strip edge, and removing the further comb remaining in clamping cooperation with the loops, finishing the tightening action of the comb that has engaged the ends of the threads, releasing said comb and urging the third comb into operative position in the place of the first comb to make the end of the remaining thread warp lie over the location of a further perforated strip.

5. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks and adapted to clamp said threads between their heads and said hooks when said pressure members are in their outer operative position, and a common member operatively connected to the different pressure members and adapted to move in a direction parallel with the hook stems and means controlling the movements of last mentioned member for bringing the pressure members carried thereby into and out of their operative positions registering with the hooks.

6. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks and adapted to clamp said threads between their heads and said hooks when said pressure members are in their outer operative position, and a common member operatively connected to the different pressure members and adapted to move in a direction parallel with the hook stems, means for controlling the movements of last mentioned member for bringing the pressure members carried thereby into and out of their operative positions registering with the hooks, springs connecting the inner ends of the pressure members with the corresponding member controlling the latter for yieldingly urging the pressure members towards the hooks and absorbing the reaction produced by the clamping of the threads between the hooks and the pressure members.

7. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, a common member operatively connected to the

different pressure members and adapted to move in a direction parallel with the hook stems and means controlling the movements of last mentioned member for bringing the pressure members carried thereby into and out of their operative positions registering with the hooks.

8. In an arrangement for knotting threads over sample cards including a carrier plate for perforated strips that are to form the sample cards, said carrier plate comprising projecting teeth folded back to form with the remainder of the carrier plate in register with the intervals separating the location of the perforations in said strips a guide for the introduction of the perforated strips, at least one adjustable stop adapted to be secured to the carrier plate at an adjustable point thereof, a spring blade rigid with said stop for urging the perforated strip into contact with the carrier plate and at least two combs comprising each a body, a number of parallel hooks including stems rigid with the comb body, each hook being adapted to engage a thread through a perforation of the sample card strip, an equal number of pressure members

35

35. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

40

40. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

45

45. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

50

50. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

55

55. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members

60

60. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

65

65. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members slidably carried by the comb body in register with said hooks including heads provided with an axial slot the sides of which slidably engage the cooperating surfaces of the hook stems and are adapted to exert a clamping action on the threads engaged between said sides of the slot and cooperating hooks, the heads of the pressure members having oblique surfaces for the gradual clamping of the threads between same and the corresponding hooks, a common member operatively connected to the different pressure members and adapted to move in a direction parallel with the hook stems and means controlling the movements of last mentioned member for bringing the pressure members carried thereby into and out of their operative positions registering with the hooks.

70

70. In an arrangement for knotting threads over perforated sample cards laid over a support, the provision of at least two combs comprising each a body, a number of parallel hooks including stems rigid with the comb body, each hook being adapted to engage a thread through a perforation of the sample card strip, an equal number of pressure members

bers slidingly carried by the comb body in register with said hooks and adapted to clamp said threads between their heads and said hooks when said pressure members are in their outer operative position, a common member operatively connected to the different pressure members and adapted to move in a direction parallel with the hook stems and means controlling the movements of last mentioned member for bringing the pressure members carried thereby into and out of their operative positions registering with the hooks.
